FIRE EXTINGUISHER

Clifford B. White and Charles H. Lindsay, Elmira, N. Y., assignors to American-La France-Foamite Corporation, Elmira, N. Y., a corporation of New York

Application July 8, 1943, Serial No. 493,930

5 Claims. (Cl. 169—32)

This invention relates to fire extinguishers which function by the effect of chemical reaction and which are required to be installed in situations where the temperature may vary from many degrees below zero to many degrees above. Its object is to adapt such apparatus to project extinguishing liquid, which may be foam, in a stream which is neither too forceful at the higher temperatures when chemical action is vigorous, nor too feeble at the lower temperatures when such action is sluggish.

This object is obtained by the employment of a thermostatic valve, which can be of simple design and therefore reliable in action, for controlling the communication between the mixing space or reaction zone in the extinguisher and a supplemental compartment containing either a reserve supply of one of the reacting chemicals or a special chemical. Such valve opens or permits the opening of its compartment by the effect of temperature and thereby adds its chemical to the reacting solutions in such way as to balance the effect of an extreme temperature or as circumstances require. Extinguishers operating on this new principle can be variously designed and the two forms herein shown are merely exemplary.

In the drawing,

Figure 1 represents an extinguisher in elevation with parts broken away and interior parts shown in section;

Figure 2 is a cross section on line II, II of Figure 1, and

Figure 3 is a modified form of supplemental compartment and valve.

The extinguisher body may comprise the conventional main receptacle 1 provided with a hose and nozzle as usual, and a screw cap cover 2. This receptacle may be assumed to contain the main body of extinguishing liquor, say a solution of sodium or potassium bicarbonate, termed solution B, liberally dosed with a polyhydric alcohol, or other suitable depressant, to keep it from freezing at the low temperature, say -40° F. Specifically, we have used for the B solution 2 lbs. of KHCO_3 , 4 quarts water, 3 quarts ethylene glycol and a foam stabilizer.

The main receptacle also contains an inner receptacle 3 removably supported by the cage structure 4 from the cover 2 or in the neck opening. This inner receptacle 3 contains the companion reagent or solution A which is one adapted to react with the soda to evolve carbon dioxide gas and thereby furnish the internal pressure for expelling the extinguishing liquid through the

outlet hose and nozzle. The pressures ordinarily required are about 90 pounds for liquid streams, and 45 or 50 pounds when the stream is foam. The solution is of course selected according to the reaction desired, with an alcohol or the like present to prevent freezing. We have used an acid-reacting solution of aluminum sulfate $\text{Al}_2(\text{SO}_4)_3$, 20 oz. in 1 quart of water with 4 oz. of conc. sulfuric acid or other non-fuming acid.

10 The reaction of solutions A and B occurs in the present case on the inversion of the extinguisher, at which time the stopple 5 falls away from its seat and the two liquids mix together and react, but any other means of bringing about contact and reaction can of course be employed.

In the main container there is also located the supplementary receptacle or compartment indicated at 6 in Figures 1 and 2. This is for the supplemental reagent or solution C. It can be of smaller capacity than the A receptacle and has a cover or valve 7 which is hinged (at 8) and adapted to be held closed by a latch member 9 hooking over the free edge of the cover. This latch is constituted of or controlled by thermostatic material which gives it a hook-shape at moderate temperatures and higher, but straightens out at lower temperatures. It thus holds the valve closed under part of the temperature range but unlocks it in the other part of the range so that it also may fall away from its seat on inversion.

35 The C solution of the supplemental compartment is thus admitted to the reaction zone only when the temperature conditions require it. Such solution may comprise or consist of any vigorous acid-reacting substance, suited to the other reagents, for example stannic chloride diluted in water and glycol, or any member of the group of reagents which comprises: AlCl_3 , SnCl_4 , SiCl_4 , TiCl_4 and SbCl_5 . The effect of this additional stronger solution is to supplement or stimulate the gas production of the A and solutions and thereby develop instantly the proper expelling pressure to give the proper stream. The relative proportions of the three solutions are selected according to the nature of the reagents used and so as to produce the effect just stated. With A and B solutions as above described we have used 180-200 cc. of anhydrous SnCl_4 in 250 cc. of a 25% solution of ethylene glycol, but there is no limitation to specific proportions or dilutions since they may be combined to evolve the proper volume of gas according to preference.

50 55 It may be assumed that both the A and C solu-

tions react with the base to liberate CO_2 in cold weather operation, the action of the latter greatly predominating, whereas in warm weather operation the reaction may be solely or mainly by the A solution, according to the thermostat design. The glycol it will be understood functions merely as a freeze-point depressant.

In Figure 3 the same principle is incorporated in a form in which the supplemental reagent is admitted to the reaction zone at a rate more or less proportional to the temperature change. In this form the supplemental receptacle 10 has a piston or slide-valve type of cover 11 supported on a thermostatic bellows 12 resting on a cross brace 13. The expansive tendency of the bellows is balanced against the pressure of a spring 14 so as to hold the valve in a closed position indicated in full lines at the higher temperature. When the temperature falls toward the other end of the range of the shrinking of the bellows allows the spring to push the valve downward more or less to the dotted line position, which opens the compartment. The bellows, valve and spring are connected respectively to each other and to the screw cap 15 so that they can be removed with the latter, as a unit, when the supplemental compartment is to be replenished. The cylindrical skirt of the piston 11 can be dimensioned in relation to the tapered opening it controls to give a proper graduation for the flow of the C solution into the mixing space making it apparent that in middle range operations not all of this solution will be used to produce the discharge.

We claim:

1. An extinguisher of the type comprising normally separated reagents adapted for evolving gas for creating pressure for expelling the extinguishing medium, including a supplemental compartment containing a reagent adapted to affect the gas evolution of the first named reagents, and a thermostatically governed valve device for

said compartment adapted for retaining and preventing the use of the contents thereof in one extreme of temperature condition and releasing such contents in the other extreme.

5 2. An extinguisher of the type comprising normally separated gas-producing reactive solutions, including a supplemental compartment containing a third reagent and a thermostatically governed valve device controlling the outlet of said compartment.

10 3. An extinguisher comprising a receptacle for basic solution, a companion receptacle for a relatively weak-acid-reacting solution, a third receptacle for a relatively strong acid reacting solution, means for causing the flowing together of said solutions to operate the extinguisher, and a thermostatic valve device controlling the flow out of said third receptacle.

15 4. An invertible type extinguisher comprising a main receptacle containing basic solution and freeze-point depressant, an inner receptacle containing an acid-reacting solution of low freezing point adapted to mingle with the other on inversion to produce gas, a third receptacle containing a supplementary solution also of low freezing point and capable of supplementing the gas production of the others, at low temperatures and a valve device controlling the entry of the latter solution into association with the other solutions.

20 5. A fire extinguisher comprising a main receptacle containing a low-freezing solution and another receptacle containing a different solution reactive with said first solution, the latter receptacle having a valved outlet opening into the main receptacle and a thermostat controlling the valve of said outlet and thereby governing the rate of flow from said latter receptacle into the main receptacle.
